United States Patent Office

Des. 221,558
Patented Aug. 24, 1971

221,558

ANIMAL BED

Robert O. Zimmerman, 33542 Morris St.,
Wayne, Mich. 48184

Filed Apr. 3, 1970, Ser. No. 22,236

Term of patent 14 years

Int. Cl. D30—06

U.S. Cl. D30—41

FIG. 1

FIG. 2

FIG. 3

FIG. 4

FIG. 1 is a top plan view of an animal bed showing my new design;

FIG. 2 is a side elevation thereof taken on line 2—2 of FIG. 1, the side opposite being a mirror image;

FIG. 3 is a front elevation thereof taken on line 3—3 of FIG. 2; and

FIG. 4 is a rear elevation thereof taken on line 4—4 of FIG. 2.

The bottom of the design is substantially plain and unornamented.

I claim:

The ornamental design for an animal bed, as shown and described.
